FIG. 1.

FIG. 2.

FIG. 3.

FIG. 4.

Inventor

C. E. Reyburn.

By *Lacy, Lacy*, *Attorneys*

UNITED STATES PATENT OFFICE.

CHARLES E. REYBURN, OF PERU, INDIANA.

WEATHER STRIP.

Application filed March 22, 1927. Serial No. 177,371.

The present invention is directed to improvements in weatherstrip.

The primary object of the invention is to provide a device of this character so constructed that it will retain its elasticity indefinitely.

Another object of the invention is to provide a device of this character which is simple in construction, durable, and one which can be easily and quickly secured to a door or window frame, and when in place will effectively prevent the entrance of air and dust.

In the accompanying drawing:

15 Figure 1 is a side elevation of the device, the felt packing being broken away.

Figure 2 is a sectional view on line 2—2 of Figure 1.

20 Figure 3 is a side elevation of a modified form of the invention, the packing being broken away.

Figure 4 is a similar view, of another modified form of the invention.

Referring more particularly to Figures 1 and 2 of the drawing, 1 designates a channel member formed of suitable gage sheet metal, the leaf 2 thereof being greater in width than the leaf 3. A fabric packing 4 preferably of felt, is employed and is folded 30 to provide plies 3' and 4', and it is between these plies that the spring element 5 is placed before it is secured to the channel member.

This element is formed from a single length of suitable gage resilient wire so bent as to include a plurality of coils 6 and angularly disposed terminals 7. It will be observed that the terminals 8 of the coils extend in opposite directions and are in the same plane in order to provide, in effect, a continuous bar 9, which will rest in the fold 10 of the packing 4 so that the edge of the packing will evenly engage the window or door.

After the spring element 5 has been placed between the plies 3' and 4', the coils 5 are inserted between the leaves 2 and 3 of the channel member 1, which is punched

as at 11, at points within the coil to maintain said elements in firm fixed relationship with the channel member. Securing devices are engaged in the punched opening for securing the channel member on a door or window frame.

In the modified form of the invention, as shown in Figure 3 of the drawing, the spring element 12 is formed also from a single length of wire, bent to provide oppositely disposed substantially triangularly shaped loops 13, the arms of the outermost loops terminating in extensions 14 which are disposed in a plane with the bars 15 of said loops, the inner bar 16 thereof being engaged in the channel member and secured therein by crimping the leaves 17 and 18 thereof. The side arms 19 of the respective loops are provided with coils 20 to enhance the resiliency thereof. The spring element 12 is placed in the packing 21, as in the preferred form of the invention.

In the modified form of the invention, as shown in Figure 4, the spring element 22 is likewise formed from a single length of resilient wire and is so bent as to provide loops 10, heads 23 and connecting coils 24, the horizontal bars 25 of said heads being in the same plane. This element as in the preferred form is also placed in a packing 26 and is secured in the channel member 27 in any suitable manner.

It will be observed that when the device is in its operative position the spring element will hold the packing in yieldable engagement with the door or window with sufficient tenacity to prevent the entrance of air and dust. Further, it will be observed that these elements are so constructed that they will adjust themselves to any uneasiness which may occur in the woodwork, thus assuring a tight joint.

Having thus described the invention, I claim:

1. A weatherstrip comprising a resilient element, consisting of a single length of wire bent to provide spaced coils for disposition in longitudinal alignment, the ter-

minals of which are extended in opposite directions and in the same plane, and a packing enclosing the element.

2. A weatherstrip comprising a channel member, a resilient element formed from a single length of resilient wire bent intermediate its ends to provide longitudinally spaced coils having oppositely extended terminals disposed in the same plane, the ter-

minals of the outermost coils being disposed in angular relation with respect to the oppositely extended terminals of the coils the coils of the elements being fixed in the channel member.

In testimony whereof I affix my signature.

CHARLES E. REYBURN. [L.S.]
